US0D1035585S

(12) **United States Design Patent** (10) **Patent No.:** **US D1,035,585 S**
(45) **Date of Patent:** **** Jul. 16, 2024**

(54) **CONNECTOR**

(71) Applicant: **SHANGHAI MAODOUYA AUTOMOTIVE ELECTRONICS CO., LTD.**, Shanghai (CN)

(72) Inventor: **Hechuan Xu**, Shanghai (CN)

(73) Assignee: **SHANGHAI MAODOUYA AUTOMOTIVE ELECTRONICS CO., LTD.**, Shanghai (CN)

(**) Term: **15 Years**

(21) Appl. No.: **29/923,726**

(22) Filed: **Jan. 1, 2024**

(30) **Foreign Application Priority Data**

Nov. 23, 2023 (CN) 202330767642.4

(51) **LOC (14) Cl.** **13-03**

CLAIM

The ornamental design for a connector, as shown and described.

DESCRIPTION

FIG. 1 is a front perspective view of a connector according to our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of area 9 indicated in FIG. 1; and, FIG. 10 is an enlarged view of area 10 indicated in FIG. 2. The dash-dot broken lines illustrate the bounds of the enlarged views and form no part of the claimed design. The dash-dash broken lines illustrate portions of the connector that form no part of the claimed design.

1 Claim, 10 Drawing Sheets
